ADJUSTABLE SWITCH ROD

George R. Burkhardt, Chicago, and Charles W. Breed, Western Springs, Ill.

Application May 1, 1940, Serial No. 332,814

5 Claims. (Cl. 246—451)

This invention relates to railway switches, and has generally in view to provide an improved means of connecting switch-point rails with switch rods so that small increments of adjustment of the switch-point rails relative to the switch rods may be effected to secure close disposition of the switch-point rails relative to the stock rails both initially and as wear of the stock rails occurs, particularly to the end that switches may be maintained in condition to insure the safe passage of modern, high speed trains therethrough.

It is known to provide adjustable connections between switch-point rails and switch rods. However, such adjustable connections, as heretofore provided, have afforded only rough adjustments of the switch point rails relative to the switch rods and not such fine adjustments as to compensate for small amounts of wear of the stock rails. Accordingly, a principal object of the invention is to provide a simple, practical, inexpensive connection between a switch-point rail and a switch rod so that very small increments of adjustment of the switch-point rail relative to the switch rod may be effected to insure close disposition of the switch-point rail to the side of the related stock rail when the switch is closed both initially and as small amounts of wear of the stock rail take place.

Another principal object of the invention is to provide an adjustable connection as stated between a switch-point rail and a switch rod which requires the forming of only a single hole in the switch rod. As compared with prior connections which require the forming of a plurality of holes in the switch rod the present connection therefore is exceptionally strong and durable, especially respecting any likelihood of the switch rod becoming broken due to being weakened by perforation thereof.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like characters of reference denote corresponding parts in the different views:

Figure 1 is a transverse section through one of the stock rails and one of the switch-point rails of a railway switch illustrating, in section, the

present improved means for adjustably connecting the switch-point rail with the switch rod.

Figure 2 is a top plan view of the parts shown in Fig. 1.

Figure 3 is a section on the line 3—3 of Fig. 2.

Figure 4 is a perspective view of the locking washer comprising part of the adjustable connection.

Figure 5 is an end view of the eccentric washer comprising part of the connection.

Figure 6 is a view similar to Fig. 2 illustrating an alternative embodiment of the invention.

Figure 7 is a view similar to Fig. 1 of the alternative embodiment of the invention.

Figure 8 is a view similar to Fig. 3 of the alternative embodiment of the invention.

Figure 9 is a fragmentary view similar to Fig. 6 with the locking washer removed.

Figure 10 is a view similar to Fig. 3 of an alternative embodiment of the invention.

Referring to the drawings in detail, first with particular reference to the embodiment of the invention shown in Figs. 1 to 5, A designates a stock rail, B designates a switch-point rail, C designates a switch rod, and D designates, generally, the present improved means adjustably connecting the switch-point rail B with the switch rod C.

It will be understood, of course, that while only a single stock rail and only a single switch-point rail have been shown in the drawings, the complete switch includes a second stock rail and a second switch-point rail located at the other side of the track, and that the two switch-point rails are connected together by the switch rod C for unitary actuation. It will also be understood that there is a connection D between the switch rod C and each of the switch point rails so that each switch-point rail is adjustable independently of the other relative to the switch rod C. Furthermore, it will, of course, be understood that adjustable connections between the switch-point rails and the switch rod are necessitated due to the switch rod having a fixed amount of movement for opening and closing the switch.

The switch rod C extends, as usual, transversely of the track beneath the rails and is connected with the switch point rail through the instrumentality of a clip or bracket 10 secured rigidly to the switch point rail.

In the present instance the clip or bracket 10 is of substantially L-shape in side elevation and includes a vertical arm 11 and a horizontal arm 12, the former of which is bolted to the switch-point rail as indicated at 13 and the latter of

which is of U-shape in cross section and includes upper and lower, spaced jaws 14 and 15 between which the switch rod C, of horizontally disposed, flat bar stock form, is accommodated.

In the jaws 14 and 15 are vertically alined 5 openings 16 and 17, respectively, and in the switch rod C is a smaller opening 18. These openings 16, 17 and 18 may be of circular shape as indicated or they may be square, hexagonal, octagonal or any other suitable polygonal shape.

Connecting the clip or bracket 10 with the switch rod C is a bolt 19 which includes a shank 20 extending through and closely fitting the opening 18 and upper and lower, alined disk-like portions 21 and 22 disposed in and closely fitting the openings 16 and 17 respectively. The axis of the shank 20 is laterally offset with respect to the common axis of the disk-like portions 21 and 22, or, in other words, the shank 20 is eccentrically related to the disk-like portions 21 and 22. Accordingly, assuming that the switch rod C is held against longitudinal movement, it is apparent that by rotating the bolt 19 the switch-point rail B will be adjusted toward or away from the stock rail A depending upon the direction of rotation of the bolt 19, since the bolt 19 with its disk-like portions 21 and 22 eccentrically related to its shank 20 provides a crank connection between the clip or bracket 10 and the switch rod C.

The lower disk-like portion 22 is in the form of a thick washer formed separately from the bolt 19 and removably engaged with the shank 20 thereof to permit insertion and removal of the shank into and from the opening 18 during assembly and disassembly of the connection D. On the other hand, while the upper disk-like portion 21 also may be formed separately from the bolt 19, it preferably is formed as an integral part of said bolt and carries at its top a head 23 of square or other suitable polygonal shape to be engaged by a wrench or any other suitable implement for the purpose of rotating the bolt to effect adjustment of the clip or bracket 10 longitudinally of the switch rod C.

It is essential that at least one of the disk-like portions 21, 22 be non-rotatable with respect to the bolt shank 20. If the upper disk-like portion 21 is formed as an integral part of the bolt it is, of course, non-rotatable with respect to the bolt shank. If, on the other hand, the said upper disk-like portion is formed as a part separate from the bolt it may be secured against rotation relative to the bolt shank in any suitable manner. Likewise, the lower disk-like portion as washer 22 may be secured against rotation relative to the bolt shank in any desired manner, as, for example, by having a non-circular opening 24 therein accommodating a non-circular portion of the bolt shank, as illustrated in the present instance.

When the bolt 19 is operatively engaged with the clip or bracket 10 and the switch rod C it is held against downward movement by engagement of the lower face of the upper disk-like portion 21 with the upper face of the switch rod C, and against upward movement by engagement of the upper face of the lower disk-like portion or washer 22 with the under face of the switch rod, the said lower disk-like portion or washer 22 being secured on the bolt by means of a nut 25 threaded on the lower end portion of the bolt shank in underlying relationship to said lower disk-like portion or washer and held against loss from the bolt shank by a cotter pin 26 or by any other suitable means.

To secure the bolt 19 in various different rotatably adjustable positions a locking washer 27 is engaged with the head 23 of the bolt, non-rotatively with respect thereto, and is provided on opposite sides thereof with pins or lugs 28 and 29, either for engagement in any one of a series of small holes 30 formed in the upper jaw 14 of the clip or bracket 10 and disposed in angularly spaced relationship to each other in a row concentric to the common axis of the openings 16 and 17 and the disk-like portions 21 and 22.

In the present instance the bolt head 23 is square and the locking washer 27 has a square hole 31 to accommodate said bolt head, whereby the washer and the bolt are held against rotation relative to each other. The pins or lugs 28 and 29 are disposed equal distances from the center of the washer, but are angularly spaced apart and, moreover, are disposed unsymmetrically with respect to the opening 31. The washer is reversible to dispose either side thereof and, consequently, either pin or lug 28 or 29 thereof, downwardly, and since said pins or lugs are angularly spaced apart and are unsymmetrically related to the opening 31, it is apparent that when the washer is disposed with one side thereof downwardly and with the pin or lug at the under side thereof in any one of the openings 20 the bolt 19 will be held in a certain position of rotative adjustment, whereas, by reversing the washer to dispose its other side and its other lug downwardly and by engaging the latter lug in the same hole 30, the bolt 19 will be held in a different position of rotative adjustment. This is true with respect to each of the holes 30. Moreover, the angular spacing of the pins 28 and 29 and of the holes 30 is such that the amount of rotation required of the bolt 19 to permit either pin 28 or 29, by reversal of the washer, to be engaged in any given hole 30, is relatively small. Any small amount of rotation of the bolt 19 corresponds to a small increment of adjustment between the clip or bracket 10 and the switch rod C. It will therefore be apparent that the present connecting means D provides for securing small increments of adjustment between the switch-point rail B and the switch rod C to insure close disposition of the switch-point rail to the side of the stock rail A when the switch is closed, both initially and as wear of the stock rail takes place.

The locking washer 27 may be held removably, reversibly assembled with the head 23 of the bolt 19 in any suitable manner, as, for example, by means of a cotter pin 32 inserted through a transverse hole in the bolt head above said locking washer. With reference to this phase of the invention a feature of practical importance is that of disposing the said head 23 of the bolt eccentric to the shank 20 thereof so that the locking device is independent of the rod, and a reduced number of parts can effectively be utilized to obtain the desired locking action.

By removing the nut 25 from the bolt shank 20 the bolt may be lifted to release the switch rod C for lateral removal from the clip or bracket 10 through the open side of the U-shaped arm 12 thereof, while to connect the switch rod with said clip or bracket 10 the switch rod first is inserted through the open side of the U-shaped arm 12 to a position between the jaws 14 and 15, the eccentric washer 22 then is inserted in the opening 17, the bolt 19 then is inserted downwardly and the nut 25 then is applied to the lower end of the bolt shank. Following the assembly,

the bolt is rotated to secure a desired adjustment of the clip or bracket 10 longitudinally relative to the switch rod C and the locking washer 27 then is applied to the bolt head with one side or the other of the waser disposed downwardly, depending upon which pin 28 or 29 more nearly aligns with one or another of the holes 30.

Obviously, instead of the arm 12 being disposed horizontally, said arm may be disposed vertically to permit the switch rod to be disposed with its flat sides extending vertically instead of horizontally as shown, which may be desirable in some case. In this connection, Figs. 6 to 9 of the drawings illustrate a practical, alternative embodiment of the invention in which the switch rod is disposed with its sides extending vertically.

According to the Figs. 6 to 9 embodiment of the invention the arm 12' of the clip or bracket 10' is not of U-shape in cross section as in the Figs. 1 to 5 embodiment of the invention, but comprises a single, horizontally disposed plate having an opening 16' therein, while the switch rod C', which is disposed with its sides extending vertically as aforesaid, instead of being accommodated in a U-shaped arm 12 as in the Figs. 1 to 5 embodiment of the invention, has riveted, bolted or otherwise fixed thereto a bracket 33 having a laterally offset U-shaped portion including upper and lower horizontally disposed arms 34 and 35, respectively, between which the arm 12' is accommodated. In the arms 34 and 35 are openings 36 and 37, respectively, which are axially aligned and which may be of circular, square, hexagonal, octagonal or other suitable polygonal shape as in the case of the openings 16, 17 and 18 of the first described embodiment of the invention. In any event, the opening 36 in the arm 34 is of larger diameter than the opening 16' in the arm 12', the opening 16' is larger in diameter than the opening 37 in the arm 35, and the bracket 33 is connected with the arm 12' by a bolt 19' which includes a shank 20' extending through and closely fitting the opening 37 and disk-like portions 38 and 39 disposed in and closely fitting the openings 36 and 16', respectively. The disk-like portion 38 is axially aligned with the shank 20', but the disk-like portion 39 is eccentrically related to the shank and said disk-like portion 38. Consequently, assuming that the switch rod C' is held against longitudinal movement, it is apparent that by rotating the bolt 19' the bracket 10' and the switch point rail to which it is connected will be adjusted toward or away from the stock rail depending upon the direction of rotation of the bolt 19'.

The bolt 19' is downwardly insertable into and upwardly removable from the openings 36, 16' and 37, and when it is operatively applied its portions 38, 39 and 20' are maintained associated with the openings 36, 16' and 37, respectively, because the lower face of the portion 38 rests upon the upper face of the arm 12', the lower face of the portion 38 rests upon the upper face of the arm 35 and because a nut 25' threaded on the lower end portion of the shank 20' holds the bolt against upward movement.

As in the case of the Figs. 1 to 5 embodiment of the invention, a locking washer 27' has a polygonal opening accommodating the polygonal head 23' of the bolt 19' and is provided at one or both sides with a lug 29' to be disposed in any one of a plurality of openings 30' in the arm 34 to hold the bolt 19' in different rotatably ad-

justed positions. In other respects the Figs. 6 to 9 embodiment of the invention is, or may be, the same as the Figs. 1 to 5 embodiment of the invention.

According to the embodiment of the invention illustrated in Fig. 10 the construction is the same as illustrated in Figs. 1 to 5, except that the switch rod, designated as C', is in the form of a pipe or tube of steel or other suitable material instead of solid, rectangular form in cross section as illustrated in the other embodiments of the invention. The special advantages of the rod C' are that it is light in weight and, at the same time, exceptionally strong and durable. While said rod might simply be provided with a hole to directly accommodate the shank 20' of the bolt 19', said rod preferably has inserted in a transverse hole therein a bushing 40 of Haschrome or other suitable material to afford a bearing for the shank 20' from top to bottom of said switch rod. The bushing 40 may be secured in the rod C' in any suitable manner as, for example, by being welded thereto as indicated at 41. In other respects the Fig. 10 form of the invention is, as aforesaid, the same to all intents and purposes as the Figs. 1 to 5 form of the invention. It will be understood, however, that a tubular switch rod may be used in a form of the invention as illustrated in Figs. 6 to 9, or in various other specifically different forms of the invention.

Without further description it is thought that the features and advantages of the invention will be readily apparent to those skilled in the art, and it will of course be understood that changes in the form, proportion and minor details of construction may be resorted to, without departing from the spirit of the invention and scope or the appended claims.

We claim:

1. Adjustable connecting means between a railway switch-point rail and a switch rod comprising a bracket secured to the switch-point rail and having an opening therein, a bolt including a disk-like portion disposed in said opening and a shank eccentrically related to said disk-like portion and disposed in an opening in the switch rod, whereby the bracket and the switch point rail are adjustable along the switch rod by rotation of said bolt, a head on the bolt, a locking washer reversibly engageable with said bolt head, means to hold said locking washer against rotation relative to the bolt head, said bracket having a series of spaced apart holes therein arranged in a row concentrically about the axis of the opening in said bracket which accommodates the said disk-like portion of said bolt, and a pin on each side of said washer for selective engagement in any one of said openings, said pins being angularly spaced relative to each other and being disposed unsymmetrically relative to the means for holding the washer against rotation relative to said bolt head.

2. Adjustable connecting means between a railway switch point rail and a switch rod comprising a bracket secured to the switch-point rail and having an opening therein, a bolt including a disk-like portion disposed in said opening and a shank eccentrically related to said disk-like portion and disposed in an opening in the switch rod, whereby the bracket and the switch point rail are adjustable along the switch rod by rotation of said bolt, a head on the bolt, a locking washer non-rotatably engageable with said bolt head, said bracket having a series of spaced

apart holes therein arranged in a row concentrically about the axis of the opening in said bracket which accommodates the said disk-like portion of said bolt, and a pin on said washer for engagement in any one of said series of holes to hold the bolt in any one of a plurality of different positions of rotative adjustment thereof.

3. An adjustable connecting means between a railway switch-point rail and a switch rod comprising a bracket secured to the switch-point rail and having an opening therein, a bolt including a disk-like portion disposed in said opening and a shank eccentrically related to said disk-like portion and disposed in an opening in the switch rod, whereby the bracket and the switch point rail are adjustable along the switch rod by rotation of said bolt, a polygonal head on the bolt, a locking washer having a polygonal opening therein to accommodate said bolt head, said bracket having a series of spaced apart holes therein arranged in a row concentrically about the axis of the opening in said bracket which accommodates the said disk-like portion of said bolt, said washer being reversible and having a pin on each side thereof for engagement in any one of the holes of said series to lock the bolt against rotation, said pins being angularly spaced apart and being disposed unsymmetrically with respect to the said polygonal opening in said washer.

4. Adjustable connecting means between a

railway switch-point rail and a switch rod comprising a bracket secured to the switch-point rail, a bolt connecting said bracket with said switch rod and having portions eccentrically related to each other and, respectively, engaged with the bracket and the switch rod so that by rotation of the bolt the bracket is adjusted longitudinally relative to the switch rod, said bracket having an arcuate series of spaced apart holes therein concentrically arranged with respect to the portion of the bolt engaged by the bracket, and a locking washer non-rotatably engaged with said bolt and having a pin for engagement in any one of said openings to secure the bolt against rotation in any one of a plurality of positions of rotative adjustment thereof.

5. Adjustable connecting means between a railway switch-point rail and a switch rod comprising a bracket secured to the switch-point rail, a bolt connecting said bracket with said switch rod and having portions eccentrically related to each other and, respectively, engaged with the bracket and the switch rod so that by rotation of the bolt the bracket is adjusted longitudinally relative to the switch rod, a member non-rotatably connected with said bolt, and interengageable means on said member and said bracket for holding said member and said bolt in different rotatably adjusted positions.
